(57) **CLAIM**

The ornamental design for a ventilator blade, as shown and described.

DESCRIPTION

FIG. 1 is a perspective view of a ventilator blade;

FIG. 2 is a front view thereof;

FIG. 3 is a top view thereof;

FIG. 4 is a right-side view thereof;

FIG. 5 is a left-side view thereof;

FIG. 6 is a rear view thereof; and,

FIG. 7 is a bottom view thereof.

The broken lines depict unclaimed portions only and form no part of the claimed design.

The dot-chain lines depict boundaries between unclaimed and claimed surfaces and form no part of the claimed design.

1 Claim, 7 Drawing Sheets(56)
